UNITED STATES PATENT OFFICE

2,254,391

COATING APPARATUS

Andrew B. Peterson, Hoquiam, Wash., assignor to
 Harbor Plywood Corporation, Hoquiam, Wash.,
 a corporation of Delaware

Application April 28, 1938, Serial No. 204,758

3 Claims. (Cl. 91—49)

This invention relates to apparatus for coating sheet or slab material and more specifically relates to apparatus for glue coating wood veneers to form cores for plywood.

In the manufacture of weatherproof plywood for outdoor use, thermo-setting binders are used to permanently unite the constituent plies of a panel. It has been found that best gluing results are obtained when a thin, aqueous solution of a thermo-setting binder is first applied to the core sheet or veneer for penetration into the wood to a desired depth. This coating is dried under controlled conditions and the thus coated core sheet or veneer then receives a heavier coating of the thermo-setting binder thereon. The heavier coating remains on the surfaces of the core and is dried under controlled conditions.

According to this invention there is now provided apparatus for the coating of core sheets and veneers. The apparatus of this invention can be operated by one person feeding the uncoated cores into one end of the device.

The machine of this invention includes a first roller coating device, a first drying device, a second roller coating device, and a second drying device arranged in tandem relationship with a single drive means controlling the operation of the entire apparatus.

The coating machines are especially adapted for the application of thin films over both broad faces of a wood veneer sheet. The machines can be adjusted to apply an even film of any desired thickness over such broad faces of the wood veneers.

The drying apparatus following each coating machine include heating means and air circulation devices for drying the coating on the wood veneers at a rate and to a degree found desirable.

Interconnected conveyors carry the veneer sheets through the coating machines and the driers. The sheets automatically pass from one conveyor to another without manual aid so that an operator need only feed the sheets into the inlet end of the first coating machine.

It is then an object of this invention to provide a labor-saving coating apparatus.

Another object of this invention is to provide a device for the coating of sheet or slab material.

A further object of this invention is to provide a coating apparatus capable of being operated by one person.

Another object of this invention is to provide a machine for automatically coating core sheets for plywood.

Other and further objects of this invention will

become apparent to those skilled in the art from the following detailed description of the annexed sheets of drawings which disclose a preferred embodiment of the invention.

On the drawings:

Figure 1 is a somewhat diagrammatic side elevational view of a tandem coating and drying apparatus including coating machines of this invention.

Figure 2 is an enlarged horizontal cross-sectional view taken along the line II—II of Figure 1.

Figure 3 is an enlarged vertical cross-sectional view taken along the line III—III of Figure 1.

Figure 4 is an enlarged vertical cross-sectional view taken along the line IV—IV of Figure 1.

Figure 5 is an enlarged side elevational view of the first coating device shown in Figure 1.

Figure 6 is a top plan view of the device shown in Figure 5.

As shown on the drawings:

In Figure 1 the reference numeral 10 designates generally the first coating machine receiving the uncoated veneer sheet for applying the initial coating to the broad faces thereof. The reference numeral 11 designates generally the first drying apparatus receiving the veneer sheet from the coating machine 10.

A second coating machine 12 receives the coated veneer sheets as the same are discharged from the drier 11. The veneer sheets pass from the coating machine 12 into the second drier 13.

The passage of the veneer sheets through the entire machine is accomplished by a series of cooperating conveyors driven preferably from a single motor.

As shown in Figure 1 a veneer sheet V is fed to the first coating machine 10 by means of a conveyor 14. The conveyor 14 feeds the veneer V between the coating rolls 15 and 16 of the machine 10. After passage between the rolls 15 and 16, the veneer sheet V is conveyed on a second conveyor 17 between conveyors 18 and 19 that extend through the open ended tunnel 20 of the drier 11.

The tunnel 20 is heated by means of steam pipes 21 located beneath the upper run of the conveyor 19 and additional steam pipes 22 located above the lower run of the conveyor 18.

Air is circulated around the sheet V in the tunnel 20 by means of a fan and duct system including a fan 23 blowing air through a duct 24 and heater 25 into an inlet manifold 26 located at the discharge end of the tunnel 20.

The inlet manifold 26 as best shown in Figures 2 and 3 has a bifurcated end including a passage-

way 27 extending across the interior of the tunnel at the top thereof and a second passageway 28 extending across the interior of the tunnel along the bottom thereof. These passageways 27 and 28 open across the entire width of the tunnel toward the work inlet end of the tunnel.

As best shown in Figure 2, each passageway such as the passageway 27 has a plurality of baffles 29 and 30 therein defining sub-passageways therebetween for directing the air from the inlet 26 uniformly across the width of the tunnel.

Air is thus blown into the tunnel at the work discharge end thereof and directed toward the work inlet end to circulate around the veneer sheets passing through the tunnel without interfering with the passage of the sheet.

The air is discharged through an outlet manifold 31 (Figures 1 and 4) located at the work inlet end of the tunnel 20.

The outlet 31 likewise has a bifurcated end portion located within the tunnel and defining passageways 32 and 33 above and below the conveyors 18 and 19 respectively as best shown in Figure 4. These passageways 32 and 33 open toward the inlet passageways 27 and 28 but have closed back walls so that the air received therein is directed into the outlet 31.

The outlet 31 communicates with the inlet end of the fan 23. A vent or stack 34 is provided in the duct 24 for bleeding moist air out of the system. A damper 35 in the duct 24 can be manually adjusted to control the amount of air bled out of the system. Fresh air is introduced through the open discharge end of the tunnel 20.

Upon leaving the heating tunnel 20, the conveyors 18 and 19 deposit the veneer sheets V onto a conveyor 36. The conveyor 36 feeds the veneer sheets between the coating rolls 31 and 38 of the second coating machine 12. The thus coated veneer sheets are then conveyed on a conveyor 39 between a pair of conveyors 40 and 41 extending longitudinally through the heating tunnel 42 of the second drier 13.

Heating coils 43 and 44 extend longitudinally along the top and bottom of the heating tunnel 42. These heating coils 43 and 44 preferably only extend about two-thirds of the length of the tunnel 42 from the work inlet end thereof.

Air is circulated over the heating coils and around the work passing through the tunnel by means of a fan and duct system including a fan 45 supplying air to an inlet 46 substantially identical with the inlet 26 of the tunnel 20. Air is removed from the tunnel through an outlet 47 having a bifurcated end similar to the end of the outlet 31 of the tunnel 20. Air is discharged from the outlet 47 into a duct 48 having a vent or stack 49 therein adapted to bleed air from the system. A damper 50 controls the amount of bleeding of air.

The exit one-third of the heating tunnel has air circulated therethrough from the work discharge end thereof by means of a fan 51 that draws air through an outlet duct 52 and discharges the air into a duct or stack 53.

In the drier 13, therefore, the second coating on the veneer sheets V is dried in an atmosphere heated by heating coils 43 and 44. The tunnel 42 is of sufficient length so that the coatings will be dried before the same reach the discharge end of the tunnel. This makes possible a cooling of the veneer sheets before the same are discharged from the drier by means of unheated air drawn into the work discharge end of the tunnel.

As best shown in Figures 2 to 4 inclusive, all of the conveyors 14, 17, 18, 19, 36, 39, 40 and 41 comprise spaced parallel tracks 55 of a somewhat U-shape as shown in Figures 3 and 4. Chains 56 slide on their upper runs along tracks 55. Transverse ribs 57 are secured to the chains 56 at spaced parallel intervals. The ribs 57 carry the veneer sheets thereon.

The lower runs of the conveyors 18 and 40 extending through the tunnels 20 and 42 respectively sag downward so that their ribs 57 rest on top of the veneer sheets supported by the ribs 57 of the lower conveyors 19 and 41. These top ribs 57 prevent the veneer sheets from sliding and also hold the same against warping and buckling during the drying operation.

The coating machines 10 and 12 are identical. Therefore the first coating machine 10 need only be described. The machine 10, as shown in Figures 5 and 6, includes a frame 60. Spaced vertical side plates 61 are mounted on the frame 60 at the front and back sides thereof. Side plates 62 are mounted on top of the plates 61 and are pivoted thereto as at 63.

Each plate 61 has a bracket 64 secured to the end thereof. The brackets 64 extend above the tops of the plates 61 and 62 and have slots 64a formed therein for receiving in slidable relation thereto the ends of nuts such as 62a projecting from the pivotally mounted plates 62. The free ends of the plates 62 are thus guided in the slots 64a of the brackets 64.

Each bracket 64 has a boss portion 65 formed at the top thereof above the plate 62. Shafts 66 are rotatably mounted in the bosses 65 of the brackets. The bottom ends of the shafts 66 are threaded into bosses 67 carried on the plates 62.

The shaft 66 at the front side of the machine receives a hand wheel 68 at the top end thereof. A sprocket gear 69 is keyed to the shaft 66 below the hand wheel 68. A second sprocket gear 70 is keyed to the top of the shaft at the rear side of the machine. An endless chain 71 is trained around the gears 69 and 70 and meshes therewith so that a rotation of the hand wheel 68 will effect rotation of both shafts 66 into and out of their respective bosses 67 on the side plates 62 for raising and lowering the side plates.

The bottom coating roll 16 extends transversely between the plates 61 and has the axles 16a thereof rotatably mounted in bearing blocks 68 fixedly carried by the plates.

A feed roll 72 also extends transversely between the plates 61 alongside of the coating roll 16 and has the axles 72a thereof rotatably mounted in bearing blocks 73 slidably carried on the sides of the plates 61. The bearing blocks 73 are adapted to be moved relatively to the plates 61 by means of adjusting nuts 74 carried on the outer sides of the plates. This arrangement provides for the movement of the feed roll 72 toward and away from the lower coating roll 16.

The upper coating roll 15 extends transversely between the upper plates 62 and has the axles 15a thereof rotatably mounted in bearing blocks 75 fixedly carried by the plates 62.

A feed roll 76 extends alongside of the roll 15 between the plates 62 and has the axles 76a thereof mounted in slidable bearing blocks 77 carried by the plates 62 in the same manner in which the slidable bearing blocks 73 are carried by the plates 61.

A hopper 80 is mounted between the plates 61 and is adapted to receive glue solutions spilled from the rolls.

The hopper 80 drains into a pipe 81 feeding a pump 82. The pump 82 forces glue solution upward through a pipe 83 having a T coupling 84 at the end thereof. A vertical pipe 85 is secured in the bottom opening of the T 84 and is positioned directly over the nip between the feed roll 76 and the top coating roll 15. A pipe line 87 is also secured in the T 84 and extends into the nip between the lower feed roll 73 and lower coating roll 16.

The hopper 80 can be charged with a supply of binder solution. When the pump 82 is in operation this solution will be discharged out of the pipes 85 and 87 into the nips between the coating rolls and their respective feed rolls.

Pressure between the coating rolls and their feed rolls can be regulated by sliding the feeding rolls toward and away from the coating rolls by means of the adjusting bolts such as 74. In this manner the film thickness of glue or binder solution carried on the coating rolls can be regulated.

The pressure between the coating rolls 15 and 16 can be controlled by raising and lowering the free ends of the top plate 62. This is accomplished by rotation of the hand wheel 68. Since both shafts 66 are operated in unison the top roll 15 will not be cocked and will bear against the bottom roll 16 with the same pressure across the entire length of the nip between the rolls.

As best shown in Figures 5 and 6, the chains of the conveyor 14 are trained around pairs of sprocket gears 90 and 91. The sprocket gears 90 are carried on a shaft 92 mounted between brackets 94 carried on the main frame. The sprocket gears 91 are carried on a shaft 93 mounted between brackets 95 carried on the main frame.

The front end of the shaft 93 has a sprocket gear 96 thereon receiving a drive chain 97 there-around. The other end of the drive chain 97 is trained around a sprocket gear 98 secured on an extension of the axle 16a of the bottom coating roll 16. This same extension of the axle, as best shown in Figure 5, has a second sprocket gear 99 secured thereon driven by a drive chain 100. The drive chain 100 is trained around a sprocket 101 carried by a shaft 102 supporting sprocket gears 103 around which the chains of the conveyor 19 are trained.

The conveyor 17 has the chains thereof trained around sprockets 104 and 105 carried on shafts 106 and 107. The shaft 107 is supported in brackets 108 carried on the main frame of the machine and is driven at the rear end thereof by a motor 109. A chain 110 and sprocket 111 operatively join the shafts 107 and 102 so that a rotation of the shaft 107 by the motor 109 also causes a rotation of the shaft 102 to drive the lower conveyor 19. The rotation of the shaft 102 drives the sprocket gear 101 for driving the chain 100. The chain 100 drives the sprocket gear 99 and rotates the coating roll 16. At the same time the sprocket gear 98 is driven to drive the chain 97 which in turn drives the conveyor 14.

Rotation of the lower coating roll 16 drives the upper coating roll 15. This upper coating roll in turn drives the chain 113 operatively connected with sprockets 114 around which the upper conveyor chain 18 is mounted. This causes a driving of the upper conveyor.

The work discharge end of the lower conveyor 19 is operatively connected through a chain 115 to the conveyor 36 of the second coating machine 12. This second coating machine 12 is

equipped with the same type of chain drive system described in connection with the coating machine 10.

With this system it is obvious that the single motor 109 can drive all of the conveyors so that the veneer sheets need only be fed onto the conveyors 14 for automatic passage throughout the entire apparatus.

From the above descriptions it should be understood that the invention comprises an apparatus for handling sheets or slabs to apply a plurality of coatings to the broad faces thereof and to dry each coating after its application onto the sheets or slabs. The coating machines of the invention can be nicely adjusted to supply glue or other coating material in any desired amount to the sheets or slabs. The coatings are applied in uniform, even films and the feed rolls or doctor rolls cooperating with the coating rolls make possible the use of corrugated soft rubber coating rolls since they will not damage such soft rolls as will the usual doctor bar. The use of doctor rolls or feed rolls in place of doctor bars also makes possible the maintenance of any desired amount of pressure against the coating rolls without damaging the latter.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. A coating apparatus comprising a pair of spaced vertical plates, a coating roll extending transversely between said plates and rotatably carried thereby, a doctor roll extending between said plates alongside of said coating roll, bearing blocks carried by said plates rotatably supporting the doctor roll, means for sliding the bearing blocks relative to the plates to move the doctor roll toward and away from the coating roll, additional plates mounted on top of said plates and pivotally connected thereto, a top coating roll rotatably mounted between said additional plates above said first mentioned coating roll, a doctor roll for said top coating roll also mounted between said additional plates, and means for swinging the top plates about their pivot points for regulating the pressure between the coating rolls.

2. A coating machine comprising a pair of spaced vertical side plates, means for fixedly mounting said side plates, top plates on top of said side plates, means pivotally connecting one end of said top plates with the fixedly mounted plates, coating rolls extending transversely between said plates in superimposed relation, the lower of said coating rolls being rotatably mounted in said first mentioned plates, the top roll of said coating rolls being rotatably mounted in said pivotally mounted plates, a doctor roll for said lower coating roll rotatably mounted in said first mentioned plates, a doctor roll for said top coating roll rotatably mounted in said pivotally mounted plates, and means for swinging said pivotally mounted plates about their pivot points to adjust the pressure between the coating rolls.

3. In a coating machine including a pair of spaced vertical side plates, means for fixedly mounting said side plates, paired superimposed coating rolls, the lower of said coating rolls being rotatably carried by said side plates, doctor rolls for said coating rolls, the doctor roll for said

lower coating roll being rotatably carried by said side plates, and means for adjusting the position of the doctor rolls relative to the coating rolls, the improvement comprising top plates on top of said side plates rotatably supporting said upper coating roll and doctor roll, means pivotally connecting one end of each top plate with

5 the fixedly mounted side plate thereunder, and means for swinging said pivotally mounted plates about their pivot point to adjust the pressure between the coating rolls without changing the relative position of the upper coating roll and doctor roll.

ANDREW B. PETERSON.
